Patented Apr. 30, 1912.

UNITED STATES PATENT OFFICE.

EDGAR BOOTH AND NORMAN RUSSELL BOOTH, OF HALIFAX, ENGLAND.

ELECTRIC-LIGHTING SYSTEM.

1,024,495.

Specification of Letters Patent. Patented Apr. 30, 1912.

Application filed October 26, 1910. Serial No. 589,254.

To all whom it may concern:

Be it known that we, EDGAR BOOTH and NORMAN RUSSELL BOOTH, subjects of His Majesty the King of Great Britain, residing at Halifax, in the county of York, England, have invented a new and useful Improvement 5 in Electric-Lighting Systems, of which the following is a specification.

It has been proposed to arrange electric 10 incandescent lamps connected in series in such manner that when a lamp of the series becomes inoperative the circuit is automatically completed through a shunt circuit to such lamp thereby maintaining the flow of 15 current to the remaining lamps in the series. This has been effected by interposing in some part of such shunt circuits metal pieces which are separated by insulating material which will withstand the electro-motive 20 force thereat when the lamps are in a normal operation but which on an increase of electro-motive force thereat owing to a lamp becoming inoperative will be destroyed and then contact will be made between the metal 25 pieces so as to conduct the current through the shunt circuit and the remaining lamps of the series are maintained in operation. Now in an arrangement of this kind all that has hitherto been relied upon to break down 30 or destroy the insulating material in the shunt circuit is the above referred to increase of electro-motive force in such circuit consequent upon a lamp of the series becoming inoperative and in practice it has been 35 found to be very difficult to so arrange the metal pieces and the insulating material separating them that in every case this rise of electro-motive force shall be sufficiently great to break down or destroy the insulating material and thus establish the shunt circuit, 40 so that this arrangement has been unreliable in operation. It has also been proposed to produce a rise of potential sufficient to insure the breaking down of the insulation by placing the lamps in series with the secondary circuit of an induction coil the primary coil of which is arranged to be momentarily traversed by a current from the mains upon the failure of a lamp. 45 According to the present invention a single circuit self-induction coil is employed and the necessary rise of potential is produced by the "extra current" induced by the instantaneous and complete interruption 50 automatically or otherwise of a circuit shunting the lamps and in which the self

induction coil is included as hereinafter explained with reference to the accompanying drawings.

The improvements comprising the present 60 invention are illustrated by way of example in the accompanying drawing, in which—

Figure 1 is a diagrammatical representation of a system of installation; and Fig. 2 is also a diagrammatical representation of a 65 modified arrangement.

Referring particularly to the drawings, Fig. 1 illustrates four incandescent lamps *a* arranged in series in the usual manner across the mains *g* and *h* each lamp having a shunt 70 circuit *d* containing metal pieces *k k* which are prevented from coming into metallic contact by the insulating material *m* which preferably consists of a piece of paper. *c* is a shunt wire across the mains *g* and *h* 75 containing a resistance *r* and a switch *s* by means of which the shunt circuit *c* may be broken or interrupted. It is essential for the successful breaking down of the insulating body *m* that the break in the shunt circuit should be as instantaneous as possible and a simple and efficient way of doing this is to break such circuit at two or more 80 points simultaneously. In Fig. 1, the switch *s* is shown to break simultaneously at two 85 points viz.—at *t* and *v*. *n* is an electro-magnet and is common to both the circuit comprising the lamps *a* in series and the shunt circuit *c*. When the lamps *a* are in a normal operation the switch *s* is open and consequently the shunt circuit *c* is not completed. On the series circuit being interrupted by reason of one of the lamps *a* becoming inoperative, the shunt circuit *c* is 90 completed and broken by closing and opening the switch *s* and as the electro-magnet *n* is also contained in this circuit, on breaking it the "extra current" above referred to is produced. The effect of breaking this shunt circuit at two or more points simultaneously 95 is to prevent the "extra current" from arcing across the points of interruption and to force it to pierce and break down the insulating material *m* separating the metal pieces *k k* thereby allowing them to come 100 into contact and thereby reestablishing metallic continuity in the circuit comprising the lamps in series. It will be readily understood that the shunt circuits *d* may include a body *r* the resistance of which is approximately equal to the resistance of the 105 filament to which it forms a shunt but such 110

resistance should preferably be a non-inductive resistance. The function of these resistances r' one of which is thrown into the circuit when insulating pieces k are broken 5 down is to choke the current so that no injurious impulses can injure the lamps which are still lighted.

By means of the above described arrangement metallic continuity in the series circuit may be immediately reestablished on a lamp becoming inoperative by operating the switch s as above described, but it has the disadvantage that it is not automatic and 10 all the lamps in the series are liable to be extinguished until the switch s is so operated. The following arrangement obviates this latter disadvantage and automatically reestablishes continuity in the series circuit upon a lamp becoming inoperative.

Referring to Fig. 2, this again illustrates 20 four incandescent lamps a arranged in series across the mains g and h each lamp as before having a shunt circuit d containing metal pieces k separated by insulating 25 material m , and resistance r' . c is the shunt circuit across the mains g and h containing the resistance r , and n is the electro-magnet common to both the circuit comprising the lamps a in series and the shunt circuit c . f 30 is an iron armature attached to a spring l and to which latter is also attached the contact piece j . The normal position of the contact piece j by reason of the spring l is in contact with and bridging the terminals 35 t and v .

The manner of operation is as follows:—
On supplying current to the mains g and h if there is continuity in the series circuit, as the electro-magnet n is contained in such 40 circuit, the armature f is attracted to it and the shunt circuit c is broken simultaneously at t and v . Let it now be assumed that the filament of one of the lamps a breaks. The series circuit being thereby interrupted the 45 armature f is released and the contact piece j again comes into contact with and bridges the terminals t and v . This establishes the shunt circuit c and as the electro-magnet n is also contained in this shunt circuit it is 50 again excited and the armature f is attracted. This has the desired effect of breaking the shunt circuit at two points simultaneously viz:—at t and v , the extra current is produced and as hereinbefore de-

scribed breaks down the insulating material 55 in the circuit which forms a shunt to the lamp the filament of which has broken. Metallic continuity in the series circuit having been reestablished the armature f remains attracted to the magnet n by the current flowing through the series circuit and the shunt circuit c remains broken.

The thickness of the insulating material and of the pieces of metal separated thereby are shown increased in both the figures in 60 order to better illustrate them.

We claim—

1. In a system of series incandescent electric lighting, a main circuit, a plurality of incandescent lamps arranged in series in said circuit, each lamp having a shunt circuit from said main circuit, a pair of adjacently arranged metal pieces in each shunt circuit, insulating material arranged between said metal pieces, a shunt wire across said main circuit, means for opening and closing the circuit including said shunt wire, an electro-magnet included in said main circuit and in the circuit including said shunt wire, said circuit including said shunt wire being normally open whereby when said circuit is closed and again opened the extra current induced from said electro-magnet breaks down the said insulation material and permits current to flow through one of said 85 first-named shunt circuits.

2. In a system of series incandescent electric lighting, a main circuit, a plurality of incandescent lamps arranged in series in said circuit, each lamp having a shunt circuit from said main circuit, a pair of adjacently arranged metal pieces in each shunt circuit, insulating material arranged between said metal pieces, a shunt wire across said main circuit, a switch arranged on said 90 shunt wire, an electro-magnet included in said main circuit and the circuit including said shunt wire, and means operated by said electro-magnet for opening and closing the circuit including said shunt wire.

In testimony whereof we affix our signatures in presence of two witnesses.
